UNITED STATES PATENT OFFICE.

CHARLES CHADWICK, OF BROOKLYN, NEW YORK.

TONE-SUSTAINING MECHANISM.

Application filed January 29, 1926. Serial No. 84,710.

This invention relates to a tone sustaining mechanism for musical instruments and has for its primary object, the provision of a means for causing any sonorous body to vibrate as long as desired.

The main object of the invention however, resides in a mechanism for use in connection with a piano. Ordinarily, when the keys of a piano are struck no matter how hard, the tones fade away gradually and the pianist has no means for controlling them after once struck. Many attempts have been made since the piano has been evolved to overcome this, but with little success. One of the best methods so far, has been by the use of electro-magnets, but because the instruments of this type were too complicated and too expensive, their manufacture was discontinued. My invention relates to an entirely novel method for producing, sustaining and controlling the tones of a piano, or any other musical instrument with the exception of so called wind-instruments.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a fragmentary perspective view of a portion of a piano with my invention applied thereto.

Figure 2 is a vertical transverse sectional view on the line 2—2 of Figure 1.

Figures 3 to 7 inclusive illustrate various modified forms of my invention.

Referring more particularly to the drawings and especially to Figures 1 to 5 inclusive, the reference numeral 10 designates the action of a piano and 11 the key board therefor. Although I have illustrated my invention in connection with the piano in the preferred form, it will be seen that by reference to Figures 6 and 7 that the same may be applicable for use upon other types of musical instruments.

The action 10 includes the usual sounding board 12 adjacent to which the strings 13 are strung and are spaced from the board by a bridge 14. Journalled in bearings and extending the length of the action forward of the same, is a rotatable member 15, the same being constructed of a metal body or core 16 having an outer covering of resinous

substance 17. The substance 17 may be formed of a layer of thick felt impregnated with rosin or the rosin mixed with hair, wool or paper pulp and evenly applied to the core 60 to provide a friction producing surface on the rotatable member 15.

The key board 11 includes the usual piano keys 18, one for each respective string 13. Slidable rods 19 are operable in an upward vertical direction when the manipulating ends of the keys are depressed, and the said rods drop to normal position when pressure is released from the keys. Resting on the upper end of each rod 19 is a pivoted arm 20 which carries a reed or flat spring 21, to the free end of which is connected one end of a flexible cord 22. The cord passes beneath the rotatable member 15 and is tied to the respective string 13. 70

The flat spring or reed 21 is of the same frequency or nearly the same as that of the string to which it is attached. Further, the tone of the piano string, has besides its fundamental a number of upper partials which 80 are heard at the same time as the fundamental and which makes the tone of the instrument rich and pleasing in quality. To preserve these upper partials, the cord 22 is 85 preferably attached to the string at approximately one-twentieth of its vibrating length from either end.

For the purpose of imparting a continuous rotation to the member 15, I provide an electric motor 23 operatively connected with the 90 member 15 by any suitable transmission means 24. The rotatable member 15 turns in the direction of the arrow but if desired, the same may rotate in an opposite direction without affecting the operation of the mechanism. 95

In operation, when one of the key levers 18 is depressed, the rod 19 moves upward and in turn lifts the pivoted arm 20 upward about its pivot, thus causing the reed or 100 spring 21 to pull the cord 22 taut about one-fourth the circumference of the rotatable member 15. As the friction between the cord and the member 15 increases, the cord will be caused to vibrate and will continue to do so as long as this condition exists. This principle is similar to that produced by a bow passing over the strings of a violin, but in this instance the member 15 may be termed a rotatable "bow." 105

In Figure 3 of the drawings, I have shown a slightly modified form of my invention

in which a helical spring 21' is substituted for the reed or flat spring 21 shown in the preferred form. The operation and action is identical to that of the preferred form 5 so that a description of the same is not believed necessary.

In Figures 4 and 5, I have shown a still further modification in which the same elements are used as in the preferred form but 10 the same are arranged slightly different. Should the string be of considerable length as for instance in the lower register of a piano, it will not start with its fundamental quick enough for practical purposes, be- 15 cause of its mass. To overcome this objection, I provide either one of two methods. In Figure 4, a reed or flat spring 21^A is mounted below the rotatable member 15 forward of the string 13 and is of nearly the 20 same frequency as the fundamental of the string. Instead of attaching the end of the cord directly to the string, the said end is attached to the reed or spring 21^A at a particular point and the said reed or spring 25 21^A connected with the string at a particular point by means of a link 25. In Figure 5, the cord 22 passes about the string 13 and has its ends respectively connected to the 30 reeds or strings 21 and 21^A. When the reed 21 is raised the cord 22 will slide about the string as much as the tension of the reed or spring 21^A will permit.

In Figure 6 of the drawings, I have shown my invention as applied to a xylophone. Instead of connecting one end of the cord 22 to a spring, the same is connected with the bar 26 of the instrument above which is suspended a resonator 27. In Figure 7, I have shown the identical principle hereinbefore mentioned as applied to a diaphragm mounted within a horn 29. Having shown my invention as applied to various sonorous bodies capable of vibration, it will be appreciated that the same may be used on other types of instruments if desired.

What is claimed as new is:—

1. In a device of the class described, the combination of a sonorous member, a vibratory member of approximately the same frequency as said sonorous member, means for initially imparting a vibrating action to said vibratory member, and means sus- 50 taining the vibrating action after the ac- tuation of said first means and for trans- 55 mitting the vibration to said sonorous

member, said last means including a rotatable member and an element for transmitting energy from said rotatable member to said sonorous member after being governed 60 by said vibratory member.

2. In a device of the class described, the combination of a sonorous member, a vibratory member of approximately the same frequency as said sonorous member, means 65 for initially imparting a vibratory action to said vibratory member, a rotatable member, and co-acting means for sustaining the vibrating action of said vibratory member after the actuation of said means and for 70 transmitting the vibrations to said sonorous member.

3. In a device of the class described, the combination of a sonorous member, a vibratory member of approximately the same 75 frequency as said sonorous member, means for initially imparting a vibrating action to said vibratory member, a rotatable member, and co-acting means for sustaining the 80 vibrating action of said vibratory member after the actuation of said means and for transmitting the vibrations to said sonorous member, said co-acting means including a flexible member engageable with a friction producing surface provided on the peripheral surface of said rotatable member. 85

4. In a musical instrument, a sonorous member, a rotatable member having a friction producing surface thereon, a reed, means for vibrating said reed, and a flexible 90 member engageable with said rotatable member and adapted to transmit energy from said rotatable member to said sonorous member, the said energy being governed by 95 said reed.

5. In a musical instrument, a sonorous member, a roller having a resinous peripheral surface, means for rotating said roller, a reed of approximately the same frequency as said sonorous member, a flexible member 100 connected with said reed and engaging said sonorous member, and normally disposed out of co-acting relation with said roller but in close proximity thereto, and means for imparting vibrations to said reed for 105 causing said flexible member to frictionally engage said roller substantially as and for the purpose specified.

In testimony whereof I have affixed my signature,

CHARLES CHADWICK.
